(57) **CLAIM**

The ornamental design for a handle cushion, as shown and described.

DESCRIPTION

FIG. 1 is a top perspective view of the handle cushion design having side connector tabs with hooks facing upward.

FIG. 2 is a top plan view of the handle cushion design of FIG. 1.

FIG. 3 is a front elevation view of the handle cushion design with side connector tabs having corresponding hook and loop fasteners.

FIG. 4 is a side elevation view of the handle cushion design and shows a connector tab with loops facing downward.

FIG. 5 is a side elevation view of the handle cushion design and shows a connector tab with hooks facing upward.

FIG. 6 is a bottom plan view of the handle cushion design having connector tabs with loops facing upward.

FIG. 7 is a rear elevation view of the handle cushion design having connector tabs with loops facing upward on one connector tab and hooks facing downward on an opposite connector tab.

FIG. 8 is a perspective view of the pad rolled up and secured by the connector tabs; and,

FIG. 9 is an environmental view of the handle cushion in use on a child carrier.

The broken lines, except the pairs of dashed lines, shown FIGS. 1 through 9 are for illustrative purposes only and form no part of the claimed design.

The pairs of broken lines shown as dashes extending from end to end on connector tabs of FIGS. 1, 2, and 6–9 are for the purpose of showing stitches on the connector tabs and form a part of the claimed design.

1 Claim, 3 Drawing Sheets
